UNITED STATES PATENT OFFICE.

HYLAND L. CUSICK, OF PITTSBURGH, PENNSYLVANIA.

AUTOMATIC WEATHER STRIP.

Application filed April 29, 1919. Serial No. 293,491.

To all whom it may concern:

Be it known that I, HYLAND L. CUSICK, a citizen of the United States of America, residing at Pittsburgh, in the county of Allegheny and State of Pennsylvania, have invented certain new and useful Improvements in Automatic Weather Strips, of which the following is a specification.

The present invention relates to automatic weather strips for doors, of the type which is hinged to the door base, and when the door is closed the said strip closes the space between the door and its threshold and when the door is opened the said strip is automatically raised to permit the door to be freely opened.

The present invention being made of thin metal is comparatively light, its appearance is very good and its construction inexpensive, and therefore, much to be preferred to the commonly used wooden strips of a similar character.

In the accompanying drawings forming part of this specification I have shown one complete example of the physical embodiment of my invention, and some modified details constructed according to the best modes I have so far devised for the practical application of the principles of my invention.

Figure 1 of the drawings is an elevational view of the invention applied to the base of a door.

Figure 2 is a section on line 2—2 of Figure 1.

Figure 3 is an enlarged detail of the base of the metal strip forming part of the invention.

Figure 4 is an end view of Figure 10 taken from the left of same.

Figure 5 is a horizontal section on line 5—5 of Figure 1.

Figure 6 is a vertical elevation taken on line 6—6 of Figure 1.

Figure 7 is a vertical section taken on line 7—7 of Figure 10.

Figure 8 is a fragmentary perspective view taken on line 8—8 of Figure 2.

Figure 9 is a vertical section on line 9—9 of Figure 10.

Figure 10 is a front elevation of Figure 9.

Figure 11 is a plan view of a metal abutment used with my device.

The device consists of the following parts: The numeral 1 indicates a transverse metal

strip of a shape shown in Figure 3 hinged to the door 2 at 3 and 4, rod 5 serving as a pintle of said hinges. The metal brackets 6, 7 forming part of the hinges have an outstanding portion 8 through which the rod 5 passes as shown in Figure 1. The transverse metal strip 1 near its base is bent at an angle at 9 and is bent into a series of convolutions 10, 11 between which is held a piece of yielding material 12, preferably felt, in such a fashion as prevents the rough edges of said material from being seen. The convolutions of the bent metal strip bear compressibly against the felt 12 to hold same in position. At the top of metal strip 1 is a bent turn 13 through which the rod 5 passes forming a support for the metal strip as shown in Figure 1. Mounted on the metal strip 1 on the inner side thereof is a guide wire loop 14 of a shape shown in Figure 5 for a purpose to be described. Mounted on the door 2 beneath the metal strip 1 is a supporting bracket 15, secured to the door by screws 16, 17, etc. Passing through said supporting bracket longitudinally is a spring wire 18 the left end of which as seen in Figure 1 is returned upon itself at 19 as shown. The supporting bracket 15 at this point is slotted at 20 as shown in Figure 4 to receive the returned end 19 of the spring wire 18. The spring wire 18 has a downwardly projecting portion 21 bent as shown in Figures 1 and 10. The supporting bracket 15 is cut away at 22 to permit the downwardly projecting portion 21 of the spring wire to operate therein. The outer end 23 of the spring wire 18 has thereon an enlarged member 24, having a latch lever 25 of shape shown in Figures 8 and 1 for a purpose to be described. On the member 24 is an upstanding prong or stop 26 which limits the travel of the spring wire 18 when the latch lever 25 is rotated in a clockwise direction as seen in Figure 9. The stop 26 also is provided with an adjusting screw 27 by which means the rotary operation of the spring wire 18 can be exactly controlled. On the door jamb 28 is a flat metal strip 29 which may be either countersunk as in Figure 6, or may merely be placed on the surface of said jamb, and in either case rigidly attached thereto. The purpose of the flat metal strip 29 is to take the "wear" of the engagement of the latch lever 25 with the door jamb 28. The downwardly projecting portion 21 of the spring wire 18

is normally in engagement within the wire loop 14 as shown in Figures 8, 6 and 5. It is seen that the wire 18 being of an elastic nature resists the torsion of the latch lever 25 in an anti-clockwise direction as seen in Figure 8 on account of the returned portion 19 being held within the slot 20 of the supporting bracket 15. It is also seen that as the door 2 is closed as shown in Figure 10 6 that said latch lever 25 is thrown to the left in an anti-clockwise direction thus placing a torsional tension in the spring wire 18 and at the same time bringing the downwardly projecting portion 21 of the 15 spring wire into the position shown at 30 in Figure 6. When the metal strip 1 is in this latter position it is seen that the felt 12 closes the space between the base of the door 2 and the top of the threshold 31 at 20 point 32, and makes an air tight seal at this point. In Figure 7, I have shown a modified method of forming a stop for the rotation of the downwardly projecting portion 21 of the spring wire 18. It is seen 25 in said Figure 7 that when the wire 21 rotates to a point as at 33 that the cut out portion 35 of the bracket 15 limits the rotary travel of the said portion 21. The purpose of both the stops 26 and 36 which 30 are alternative structures is to limit the rotation of the downstanding arm 21 of the 35 spring wire 18. The numeral 37 shows a metal deflecting abutment (see Figures 1, and 11 of the drawing), having a vertically disposed plate portion 48, which is attached to the door jamb 38 by fastening means 45, a vertical bent plate portion 49, inclined with reference to the portion 48, and a horizontally disposed portion 50 formed preferably integral with the bent plate portion 49, thus forming a brace for the latter as 40 is readily understood. The purpose and use of this abutment 37 is described herein-after in this specification.

45 The operation of the device is as follows: It is at once seen that when the door is open as indicated in Figure 8 that the latch lever 25 will assume the position shown in said figure due to the normal torsional 50 "spring" in the wire 18, and that the downwardly projecting portion 21 of said wire will take the position shown at 46 due to the same cause. In this situation it is seen that the part 21 raises the metal strip 1 from the floor line upwardly about the hinge rod or pintle 5. While in this latter position it is seen that the door can be readily opened without the felt 12 engaging the floor or carpet covering same. As the door 55 is placed in the position indicated at 39 Figure 2, it is seen that the latch lever 25 engages against the plate 29 and is rotated to the position shown in Figure 6 in an anti-clockwise direction, thereby bringing the 60 part 21 and the metal strip 1 to the posi-

tion shown in Figure 6. When the device is in this position it is seen that the seal is perfect at the point 32, and no drafts can pass between the threshold 31 and the base of the door 2. As the door is opened to the 70 position shown at 47 Figure 2 the metal strip 1 takes the position shown in Figure 8 but is prevented from being raised to a higher position by the stop 26 on the part 23, which engages against the upper face 75 of the bracket 15. In like manner if the type of stop shown in Figure 7 is used when the part 21 reaches the part 36 its rotary movement is also stopped as is at once understood. It is seen that the guide wire loop 14 is much longer than is required for the entrance of the downwardly projecting portion 21 of the wire 18, so that when a door which is "sprung" and does not fit perfectly in the door jambs is 80 encountered, that the part 21 will not jam in the loop 14 as is at once appreciated from the inspection of Figures 1 and 5, and it is for this reason that the said loop 14 is made of a greater length than is necessary 85 for the mere reception of the part 21. When the door 2 is opened still further to a position shown at 40 it is seen that the outer edge 41 of the strip 1 is in the position shown in Figure 2. The square corner 42 90 of the metal strip 1 engages against the angular metal abutment 37 on portion 49 thereof, and the latter starts to depress the metal strip 1 about the rod or pintle 5 as a center 95 revolving the part 12 downward as same is 100 seen in Figures 8 and 6 of the drawing. The purpose of this arrangement is to enable the door 2 to be still further opened to the position 43 at which point the felt 12 of the metal strip 1 has approached to practically 105 its lowest position similar to that shown in Figure 6. By this arrangement it is seen that the door 2 can be completely opened due to the action of the square corner of the metal strip 1 at point 42. My 110 device can be readily adapted for various widths of doors by merely removing the rod 5 longitudinally, and shearing the edge 44 of strip 1, and the rod 5 to the desired dimensions. This is a point of considerable 115 utility in connection with the device.

From the above description it is seen that I have provided an automatic weather strip which, when the door is closed provides a perfectly tight seal for the base of the door, 120 and as soon as the door is opened the weather strip is automatically raised from engagement with the floor or carpet, allowing the door to be opened. It is seen that my structure and arrangements of parts 125 enable the door to be opened practically its full width, an arrangement which is not found in the common types of weather strips in current use.

The appearance of my type of weather 130

strip is very attractive being made of very thin metal which can be enameled in colors to match the particular color of trimmings of the wood work in the room in which it is used.

What I claim is:—

1. In a door structure, a transverse door strip provided with a corner near the hinged side of the door, adapted to engage an adjacent door jamb for the purpose of depressing said strip when the door is fully opened; a guide wire loop on the strip, automatic means for raising the door strip comprising a spring wire having a downwardly extending portion slidably engaging the guide wire loop, and an upwardly extending adjustable stop for limiting the upward movement of the strip, a latch lever on one end of said spring wire, and a returned portion at its opposite end; a supporting bracket mounted on the door, having a slotted end for receiving the aforesaid returned end of the spring wire; and a bent base on the door strip consisting of a series of convolutions of metal and yielding material formed in alternate laminations.
2. In combination with a door having a jamb a transverse door strip having a corner projecting perpendicularly to the face of the door, an inclined abutment mounted on the door jamb, and adapted to engage the corner of the door strip for gradually depressing the latter when the door is being opened to its fully opened position.
3. In a deflecting abutment adapted to engage against the edge of a door structure a transverse door strip, having a vertically disposed plate portion for attachment to the face of a door jamb, a vertical bent plate portion inclined with reference to the first described portion, and a horizontally disposed plate portion formed integrally with the vertical bent plate portion forming a brace for the latter.
4. In a door structure, a transverse door strip having a corner near the hinged side of the door, an inclined door jamb abutment which said strip is adapted to engage; a guide wire loop on the strip, a spring wire having a downwardly extending portion slidably engaging the guide wire loop, and an upwardly extending stop for limiting the upward travel of the strip, an integral latch lever on one end of said spring wire, and a returned portion at its opposite end; a supporting bracket mounted on the door, having a slotted end for receiving the aforesaid returned end of the spring wire; and a bent base on the door strip consisting of a series of convolutions of metal and yielding material in alternate laminations.

In testimony whereof I affix my signature.

HYLAND L. CUSICK.
